UNITED STATES PATENT OFFICE.

SAMUEL J. DICKEY, OF LOS ANGELES, CALIFORNIA, ASSIGNOR TO GENERAL PETROLEUM CORPORATION, A CORPORATION OF CALIFORNIA.

DEPHLEGMATOR.

Application filed September 7, 1920. Serial No. 408,670.

To all whom it may concern:

Be it known that I, SAMUEL J. DICKEY, a citizen of the United States, residing at Los Angeles, in the county of Los Angeles and State of California, have invented a new and useful Dephlegmator, of which the following is a specification.

My invention relates to dephlegmators or fractionating columns for use in the refining of petroleum oils or the like. If a crude petroleum is subjected to heat, vapors are given off which contain oils of various boiling points. It is common practice to subject the crude petroleum to a sufficient degree of heat to drive off as a vapor all of the lighter and more valuable products. This vapor may contain a considerable number of recognized commercial oils. It is the object of a dephlegmator to separate such a vapor into two components, one comprising oils of a relatively low boiling point which pass off as vapor and the other comprising oils of a relatively high boiling point which are recovered as a liquid. The low boiling point vapor may contain several commercial oils and the high boiling point recovered as a liquid may also contain several recognized commercial products.

An object of my invention is to provide a dephlegmator which will separate from a vapor a liquid having definite boiling point characteristics. The measure of efficiency of such a piece of apparatus lies wholly in the completeness of the separation. In a perfect dephlegmator none of the high boiling oils which it is desired to recover would be carried over as a vapor and none of the low boiling oils would be found in the liquid recovered. It is, of course, impossible to produce an absolutely perfect separation.

An object of my invention is to provide a dephlegmator in which large quantities of vapor may be handled with a high degree of efficiency.

A further object of my invention is to provide means by which character of the products recovered may be varied while the apparatus is in operation.

Referring to the drawings which are for illustrative purposes only.

Fig. 1 is a side elevation of my invention.

Fig. 2 is a vertical section through an upper portion thereof.

Fig. 3 is a section on a plane represented by the line 3—3 of Fig. 2.

Fig. 4 is a vertical section through a lower portion of my invention.

Fig. 5 is a section on a plane represented by the line 5—5 of Fig. 4.

Fig. 6 is a view looking down into the apparatus shown in Fig. 4.

Fig. 7 is a detail showing the baffle plate.

Fig. 8 is an enlarged fragmentary detail showing the manner in which a thorough distribution of the condensate over the baffle plates is accomplished.

In the form of my invention illustrated in the drawings, a tight metal shell is provided, this shell being divided into two parts, a lower shell 11 and an upper shell 12, for convenience in manufacture, the two shells 11 and 12 being joined by a flange 13 secured to the shell 11 and a flange 14 secured to the shell 12. The shell is pro-

vided with a tight bottom 15 having an oil outlet 16 and with a tight top 17 having a vapor outlet 18. A vapor inlet 19 is provided near the bottom of the shell 11 and the vapor to be treated is introduced therein through a pipe 20, vapor being taken away through the vapor outlet 18 by means of pipe 21. Secured to the sides of the shell 11 are headers 25 connected by tubes 26, these headers being supplied with steam or other heating medium, if desired, which passes through the tubes 26. Secured inside the shell 11 above the inlet 19 are a plurality of sections of baffle plates 30.

These plates are preferably formed of corrugated iron 31 secured together by bolts 32 and separated by spaces 33. The plates 31 are substantially parallel and form substantially vertical tortuous passages through which the vapor introduced through the inlet 19 ascends. The baffles 30 are arranged in layers in each of which the plates are turned at right angles to the layers above and below. Situated in the extreme top of the shell 12 is a perforated plate 40 and located below this plate is a series of condensing tubes 41. These tubes are arranged in sets which connect between front chambers 42 and 43 and back chambers 44.

Water is introduced into the chambers 42 through pipes 45, controlled by valves 46

and water is withdrawn from the chambers 43 by means of pipes 47. The water introduced into any chamber 42 passes through an upper set of tubes 41 into a chamber 44 and downwardly through this chamber and back through a lower set of tubes 41 into a chamber 43. The valves 46 provide means for regulating the supply of water delivered to the tubes 40. Passing crosswise 10 across the space at the extreme bottom of the shell 12 are primary deflectors 50 which are bent as shown in Fig. 2 which have open passages 51 therebetween. These deflectors are directly over troughs 55 which 15 are secured in the top of the shell 11 and which extend across that shell. The troughs 55 are provided with grooved openings 56 which discharge into troughs 57, which are also provided with grooves 58. 20 The shell 11 is provided with a heat insulating jacket 59.

The method of operation of my invention is as follows:

Vapor delivered through the pipe 20 into 25 the bottom of the shell 11 passes upwardly through the spaces between the baffles 30 and through the spaces between the various troughs and deflectors into the interior of the shell 12 which is in fact a condenser. 30 In its passage through the shell 12, the vapor comes into contact with the water cooled tubes 41 and is condensed to form a liquid which falls downwardly on to the deflectors 50 and into the troughs 55. The 35 troughs 55 tend to spread this condensate to the right and left as viewed in Fig. 6, the troughs being carefully set so that the condensate may be delivered through each of the notches 56 into the troughs 57. The 40 condensate is spread up and down as viewed in Fig. 6 in these troughs and is delivered through the notches 58 onto the top of the upper section of the baffles 30. It is quite 45 essential that the vapor shall have a uniform motion throughout the dephlegmator and for this purpose I provide the perforated plate 40 which tends to prevent a local flow, drawing equally from all portions of the shell 11. It is also important that the 50 condensates should be uniformly distributed over the baffles 30 and for this purpose I provide a deflector 50 and the troughs 55 and 57. The condensate which is uniformly distributed over the baffles 30 runs down 55 over the corrugated members 31 which form these baffles, wetting both sides thereof and covering both sides with a thin film of liquid. The ascending vapors are in very 60 intimate contact with these films due to the narrow passages between the corrugated members 31 and due also to the fact that the direction of flow of the vapors is repeatedly changed by the corrugations. During the contact of the vapor with the liquid, a redistillation and absorption takes

place, the liquid tending to absorb, from the ascending vapor, oils of high boiling point and to give up to the vapor any oils of low boiling point which may have been condensed or absorbed. As a result the 70 liquid which finally drops from the lower edge of the lower series of baffles is quite free from oils of low boiling point.

As hereinbefore stated, the efficiency of dephlegmation accomplished in any device 75 of the character herein described is dependent upon and proportionate to the area of liquid condensate to which the entering gases are exposed and brought into intimate or forcible contact with. In Fig. 8, 70 indicates the lower edge of an upper corrugated baffle plate, from which the descending absorbent liquid drops in somewhat the manner indicated at 73 which represents four streams or lines upon which the drops 80 75, 76, 77 and 78 are falling. It will be recognized that were the baffle plates indicated at 30 straight instead of corrugated, as shown, a great number of the drops 90 would fall directly through the spaces between the baffle plates. However, with the arrangement shown the drops 76 and 78 fall upon the surfaces 79 of the plates 30, and the drops 75 and 77 fall upon the surfaces 80 thereof. The downward passage 95 of all of the liquid from the plate indicated at 70 is obstructed by either the surfaces 79 or the surfaces 80, and in view of the fact that these surfaces 79 and 80 are on opposite sides of the baffle plates, both sides of the 100 baffle plates will be wetted by the downwardly travelling liquid, this liquid travelling on each plate as respectively indicated by the arrows 81 and 82. The rising vapors, as indicated by the arrows 83 and 84, 105 are deflected in their upward path so as to be brought into intimate or forcible contact with the absorbent liquid disposed on the downwardly facing surfaces 85 of the baffle plates 30, thus producing the highest efficiency in the dephlegmating action. There 110 will also be a contact of gases with the liquid disposed on the upwardly facing surfaces 87, but this contact will not be as forcible as that attained with the downwardly facing surfaces 85.

If a further refinement is necessary, the oil is allowed to accumulate in the lower portion of the shell 11 below the inlet 19 and it is reheated by means of a heating 120 medium in the tubes 26. The liquid which is finally delivered through the pipe 16 therefore contains a very definite fraction, in so far as boiling points are concerned, of the vapor delivered through the inlet 19. 125

I claim as my invention:

1. A dephlegmator comprising a shell; a series of sections, each section being formed of parallel corrugated plates forming tortuous passages through said shell having a 130

substantially vertical direction, the plates of one section being at an angle to the plates of the adjacent section; means for passing vapor into the bottom of said shell below 5 said plates; a series of water cooled surfaces in said shell above said plates; means for distributing the condensate from said surfaces uniformly over said plates; means for withdrawing a low boiling point distillate 10 in vapor form from above said condenser; and means for withdrawing a condensate of high boiling point from the bottom of said shell.

2. A dephlegmator comprising a shell; a 15 series of parallel plates forming passages through said shell in a substantially vertical direction; means for passing a vapor into the bottom of said shell below said plates; a series of water cooled surfaces in said shell 20 above said plates; means for distributing the condensate from said surfaces uniformly over said plates; means for withdrawing a low boiling point distillate in vapor form from above said condenser; means for causing 25 the vapor passing through the spaces between said water cooled surfaces to flow at a substantially uniform rate throughout said spaces; and means for withdrawing a condensate of high boiling point from the bottom of said shell.

3. A dephlegmator comprising a shell; a 30 series of parallel plates forming tortuous passages through said shell having a substantially vertical direction; means for passing a vapor into the bottom of said shell below said plates; a series of water cooled surfaces in said shell above said plates; means for distributing the condensate from said surfaces uniformly over said plates; 35 means for withdrawing a low boiling point distillate in vapor form from above said condenser; means for causing the vapor passing through the spaces between said water cooled surfaces to flow at a substantially uniform rate throughout said spaces; and means for withdrawing a condensate of high boiling point from the bottom of said shell.

4. A dephlegmator comprising a shell; a series of parallel corrugated plates forming 50 tortuous passages through said shell having a substantially vertical direction; means for passing a vapor into the bottom of said shell below said plates; a series of water cooled surfaces in said shell above said plates; means for distributing the condensate from said surfaces uniformly over said plates; means for withdrawing a low boiling point distillate in vapor form from above said condenser; means for causing the vapor passing 55 through the spaces between said water cooled surfaces to flow at a substantially uniform rate throughout said spaces; and means for withdrawing a condensate of high boiling point from the bottom of said shell. 60

5. In a dephlegmator, the combination of: a series of sections, each section being formed of parallel corrugated plates standing vertically, the plates of one section being at an angle of substantially 90° to the plates of the section next below.

6. In a dephlegmator, the combination of: a series of sections, each section being formed of parallel corrugated plates standing vertically, the plates of one section being at an angle of substantially 90° to the plates of the section next below.

7. In a dephlegmator, the combination of: a series of sections, each section being formed of parallel corrugated plates standing vertically, the plates of one section being at an angle of substantially 90° to the plates of the section next below; and means for spreading a condensate evenly over the upper edges of the upper section of said plates.

8. In a dephlegmator, the combination of: a series of sections, each section being formed of parallel corrugated plates standing vertically, the plates of one section being at an angle to the plates of the section next below; and means for spreading a condensate evenly over the upper edges of the upper section of said plates.

In testimony whereof, I have hereunto set my hand at Los Angeles, California, this 30 day of August 1920.

SAMUEL J. DICKEY.
